UNITED STATES PATENT OFFICE.

JOHN S. HARTLEY, OF LYNN, MASSACHUSETTS, ASSIGNOR, BY MESNE ASSIGNMENTS,
TO HARTLEY CLOCK COMPANY, OF BOSTON, MASSACHUSETTS.

ALARM CLOCK.

Original application filed January 17, 1914, Serial No. 812,687. Divided and this application filed January 26, 1916. Serial No. 73,138.

To all whom it may concern:

Be it known that I, JOHN S. HARTLEY, a citizen of the United States, residing at Lynn, in the county of Essex and State of Massachusetts, have invented a new and useful Improvement in Alarm Clocks, of which the following is a specification.

The present invention relates to alarm clocks.

10 Alarm clocks are usually provided with a trip lever comprising an arm of spring metal which is automatically operated to ring the alarm at a predetermined time by a cam wheel connected to one of the wheels 15 of the time train, which co-operates with a stationary alarm-set on the setting rod. When the alarm-set drops off a ledge on the cam wheel the alarm is sounded. After the alarm rings for a short time a shut-off 20 device is manually operated to engage the hammer or some other part of the alarm train for the purpose of silencing the alarm. During the continued operation of the clock the alarm-set travels up a slope on the cam 25 wheel in order to return the alarm-set to a position where it may again drop off the ledge. During its travel up the slope on the cam wheel the alarm-set operates one of the wheels of the time train to overcome the 30 spring tension on the trip lever and thus return it to a position where it again prevents the sounding of the alarm. As well known to those skilled in the art the pressure of the trip lever on the time train during the travel of the alarm-set up the slope 35 on the cam wheel acts as a brake or drag on the time train thus causing the clock to lose time or vary in rate.

The object of the present invention is 40 to relieve the time train of the braking or dragging action of the trip lever and thus improve the time keeping qualities of the alarm clock, but without preventing release of the alarm train by mechanism operating 45 independently of the means actuated by the time train.

To the accomplishment of this object, and such others as may hereinafter appear, the features of the present invention consist in 50 certain devices, combinations and arrangements of parts hereinafter described and then set forth broadly and in detail in the appended claims.

The various features of the present in-

vention will be best understood from an inspection of the accompanying drawings illustrating the preferred embodiment of the invention, in which,

Figure 1 is a left side elevation, partly in section, of the alarm clock;

Fig. 2 is a sectional elevation on the line 2-2, Fig. 1; and

Fig. 3 is a sectional detail on the line 3-3, Fig. 2.

In the illustrated embodiment of the invention the clock is provided with a gong 1 consisting of a hollow cylindrical shell secured to a casing 2 for the movement plates 3 and 4 (Fig. 1). The gong is struck to sound the alarm by a hammer 5 (Fig. 2) formed upon the upper end of an arm 6 which is secured to a rock shaft 7 mounted to rock in the movement plates. The arm 6 is connected by a link 8 to one end of a lever 9 secured to a rock shaft 10 mounted to rock in the movement plates. The lever 9 is rapidly oscillated to impart the gong striking movements to the hammer 5 by a driving gear 11, actuated in the well known manner through a train of gears, 15 hereinafter called the alarm train, from a coiled spring (not shown), cooperating with a pair of pallets 12 formed upon the lever 9.

The automatic starting and stopping of the alarm train is controlled by a spring 20 arm 13, called the trip lever, secured at one end to the plate 4. As shown in Fig. 3 the trip lever is bent near its attached end so that a pawl 14 formed upon its free end is normally held away from the gear 11. 25 To hold the pawl 14 in engagement with the gear 11 so as to stop the alarm train the trip lever is pressed upon intermediate its ends by a wheel 15 which is driven by the time train from the main spring. The 30 wheel 15 is provided with a cam wheel 16 and is loosely mounted on a setting rod 17 which controls the time at which it is desired to ring the alarm. The rod 17 is provided with an alarm-set 18 (Fig. 2) 35 which travels over the cam wheel 16. When the set 18 is in the position shown in Fig. 2 the pawl 14 is interposed between a pair of teeth on the gear 11 thus holding the alarm train from ringing the alarm. The 40 cam wheel 16 is rotated by the time train in the direction of the arrow (Fig. 2) thereby transferring the point of engagement of

the alarm-set around the cam wheel. At the time predetermined for the ringing of the alarm the alarm-set drops off the ledge 19 on the cam wheel thus freeing the trip lever to allow it to spring back to its normal position and release the alarm train to ring the alarm.

After the alarm-set drops off the ledge 19 it must travel up an incline 20 and reach 10 the normal level 21 of the cam wheel to reinsert the pawl 14 between the teeth of the alarm gear 11. As it takes four hours in some clocks and twelve hours in others for the alarm-set to travel up the incline 20 and 15 as the alarm spring is usually exhausted before the alarm has rung five minutes it is customary to provide alarm clocks with a shut-off device so that the alarm may be silenced before the exhaustion of the alarm 20 spring. Usually these shut-off devices engage the hammer to stop the alarm. With this construction the alarm-set 18 during its travel up the incline 20 operates the wheel 15 of the time train to return the trip lever, 25 against the spring tension thereof, to a position where the pawl thereon extends between the teeth of the alarm gear 11. These prior art constructions therefore caused the spring trip lever to act as a brake or drag 30 on the time train during the travel of the alarm-set 18 up the incline 20. This braking or dragging action on the time train obviously causes the clock to lose time or vary 35 its rate during the four-hour, or more, travel of the alarm-set 18 up the incline 20.

In order to relieve the time train from the braking or dragging action of the spring trip lever the illustrated embodiment of the invention is provided with a pivoted plate 40 22 arranged to engage the trip lever between the wheel 15 and the secured end of the lever. One end of the plate 22 is beveled as at 23 (Fig. 3) in order that it may ride over the trip lever, when turned from the dotted line position to the full line position (Fig. 2), and wedge it away from the wheel 15 and into engagement with the gear 11. The other end of the plate 22 is bifurcated to receive a manually operated shut-off 45 device mounted to slide on the casing 2.

With this construction the tension of the trip lever is withdrawn from the wheel 15 during the travel of the alarm-set 18 up the slope 20 on the cam wheel thus relieving the 55 time train of the brake or drag to be found in the ordinary alarm clock. The free end portion of the trip lever may be freely flexed to release the alarm train by mechanism operable independently of the time train and 60 shut-off lever. This mechanism, in the present instance, is responsive to temperature changes, and will release the trip lever to sound the alarm when the clock becomes heated to a predetermined degree.

65 This mechanism comprises a plunger 28

mounted to slide longitudinally in a yoked bracket 29 secured to the back plate of the clock works. The plunger 28 is provided with a conical end the point of which is arranged to engage a pin 30, (Figs. 2 and 3), 70 formed on the free end of the trip lever 13. When the plunger is moved forwardly its end strikes the pin 30 and removes the pawl 14 from engagement with the teeth of the gear 11 thus starting the driving mechanism 75 to sound the alarm. The pawl 14 is actuated to release the driving mechanism under the influence of the plunger 28 even when the plate 22 has been actuated to stop the time controlled movement of the alarm 80 mechanism as the trip lever is sufficiently flexible between its free end and the point of engagement of the plate 22 to permit the movement of the pawl 14 away from the gear 11.

85 The plunger 28 is normally held in an inoperative position by a coiled spring 31 coiled around the shank of the plunger and interposed between the bracket 29 and a block 32 on the rear end of the plunger. The plunger is actuated forwardly to withdraw the latch 14 by a thermostat comprising a pair of hollow connected disks 33, filled with ether, which are secured, with a fiber washer 34 interposed between the disks and the back 90 wall of the gong 1, by a bolt and nut connection 35 inside the gong. The outside disk 33 presses against a screw 36 which is adjustably held in the vertical arm of a bell 95 crank lever 37 pivotally mounted on a bracket 38 carried by the casing 2. The horizontal arm of the bell crank lever carries a point 39 which engages a cup 40 formed in the block 32. With this construction an expansion of the ether-filled disks to 100 a predetermined degree actuates, through the connections described, the plunger 28 to sound an alarm.

105 The drawings illustrate other novel features in alarm clocks, but these features are not described herein as they are disclosed in Patent No. 1,200,103, dated October 3, 1916, of which this application is a division.

110 It will be clear to those skilled in this class of clocks, having the general objects of the present invention in view, that changes may be made in the details of structure, the described and illustrated embodiment thereof being intended as an exploitation of its underlying essentials, the features thereof 115 being definitely stated in their true scope in the claims herewith.

120 What is claimed as new, is:—

125 1. A clock, having, in combination, an alarm train, a time train, a trip lever secured at one end to one of the movement plates normally arranged to tend to permit the operation of the alarm train and to press against one of the wheels of the time train, and a shut-off device for disengaging the 130

trip lever from the wheel of the time train and positioning the trip lever to stop the alarm train arranged to engage the trip lever between its secured end and the wheel 5 of the time train, substantially as described.

2. A clock, having, in combination, an alarm train, a time train, a trip lever secured at one end to one of the movement plates normally arranged to tend to permit 10 the operation of the alarm train and to press against one of the wheels of the time train, and means for disengaging the trip lever from the wheel of the time train and for locking the trip lever in position to stop 15 the alarm train arranged to engage the trip lever between its secured end and a wheel of the time train, substantially as described.

3. A clock, having, in combination, an alarm train, a time train, a spring metal arm secured at one end to one of the movement plates and normally arranged to press 20 against one of the wheels of the time train, mechanism co-operating with the time train for holding the arm in position to stop the alarm train and for releasing the arm from 25 its alarm train stopping position, and means for relieving the wheel of the time train from the braking action of the arm when the alarm is silenced arranged to engage 30 the arm between its secured end and the wheel of the time train, substantially as described.

4. A clock, having, in combination, an alarm mechanism, a driving mechanism 35 therefor, a spring metal arm secured at one end to one of the movement plates and normally disposed to tend to permit the operation of the driving mechanism, means for holding the free end of the arm in position 40 to stop the driving mechanism, a timing mechanism co-operating with said means

for releasing the arm to start the driving mechanism, and a pivoted plate having one end arranged to engage the arm between its secured end and the point of engagement 45 of said means for locking the arm to prevent its release by the timing mechanism, substantially as described.

5. A clock, having, in combination, an alarm mechanism, a driving mechanism 50 therefor, a spring metal arm secured at one end to one of the movement plates and normally disposed to tend to permit the operation of the driving mechanism, means for holding the free end of the arm in position 55 to stop the driving mechanism, a timing mechanism co-operating with said means for releasing the arm to start the driving mechanism, and a pivoted plate having one end arranged to engage the arm between its secured end and the point of engagement 60 of said means for locking the arm to prevent its release by the timing mechanism and having its other end operatively connected to a manually operated device, substantially 65 as described.

6. A clock, having, in combination, an alarm train, a trip lever for the alarm train comprising a spring metal arm secured at one end to one of the movement plates and having 70 its free end positioned for engagement with the alarm train, a time train having one of its wheels arranged to engage the trip lever intermediate its ends, and a shut-off device arranged to engage the trip lever between 75 its secured end and the wheel of the time train, the trip lever between its free end and the wheel of the time train having freedom to flex out of engagement with the alarm train when the shut-off device is in shut-off 80 position, substantially as described.

JOHN S. HARTLEY.
